UNITED STATES PATENT OFFICE.

JOHN T. HAWKINS, OF TAUNTON, MASSACHUSETTS.

CYLINDER PRINTING-PRESS.

SPECIFICATION forming part of Letters Patent No. 257,576, dated May 9, 1882.

Application filed April 18, 1881. (No model.)

To all whom it may concern:

Be it known that I, JOHN T. HAWKINS, of Taunton, in the county of Bristol and State of Massachusetts, have invented a new and useful Improvement in Cylinder Printing-Presses, which improvement is fully set forth and illustrated in the following specification and accompanying drawings.

The invention as herein set forth and illustrated is more particularly adapted to a lithographic press, or to the printing of but one side of a sheet. It embodies, however, underlying principles or leading features of machine-printing utilized and further developed in the several applications herewith filed, and marked successively B, C, D, and E.

The object of this invention is to combine in a machine of simple and durable construction all the following enumerated desirable features, which, although heretofore severally or in certain groups appearing, in more or less successful practice, in presses known by different technical names, have heretofore never all been combined in any one machine. Said features are, first, equal surface velocities of impression-cylinder and bed; second, an impression-cylinder of comparatively small diameter; third, absence of all mechanism for causing the impression-cylinder to rotate in but one direction while the bed reciprocates or makes a double stroke; fourth, absence of all mechanism for disarticulating and rearticulating the impression-cylinder and bed, peculiar to and distinctive of the well-known "stop-cylinder" press; fifth, absence of all buffers or buffer-springs for arresting the motion of the bed; sixth, the delivery of each sheet of paper upon the fly-board with its last-printed side upward and without the impression thereon having come in contact with any part of the delivery mechanism; seventh, entire absence of tapes or cords from any part of the machine; eighth, free access to the form upon the bed—a feature especially important for lithographic work, and heretofore not so well secured in lithographic presses.

This invention consists broadly in so combining or arranging the parts of a cylinder printing-press and so timing their respective movements in relation to each other that the cylinder, during its forward rotation, shall partially deliver each printed sheet head first and then be reversed to the point whence it start-

ed, retrograding under the undelivered part of the sheet still in contact with it while the delivery of the sheet is being effected by the delivery mechanism to and upon the fly-board. The motion of the sheet (though unchanged in direction throughout its whole delivery) is thus with the cylinder during its forward revolution; but throughout the cylinder's and bed's simultaneous and continuous retrogression the sheet's motion is opposed to the direction of the cylinder's motion, as the cylinder does not stop, except, like the bed, when the crank is actually turning its center. This method of delivering the sheets is therefore better adapted for lithographic impressions, or for printing but one side of the sheet, for if the sheets were printed on both sides the impression on the first-printed side would be liable to be blurred or marred in the act of drawing them from the cylinder in a direction contrary to its motion. However, by the simple employment of this novel method of delivery all difficulties of gearing the cylinder directly to the bed and reciprocating the bed by the crank motion have been successfully overcome without the use of further devices or compensating complications, while at the same time a cylinder of minimum diameter is obtained.

The construction of the machine in detail is fully set forth in the following description and accompanying drawings, illustrative of the invention, in which—

Figure 1 illustrates in side elevation a lithographic press to which this invention has been applied. Fig. 2 is a front elevation of the machine illustrated in Fig. 1, certain points hereinafter designated being omitted for the sake of clearness. Fig. 3 is a plan of the machine, the feed-board being removed in order to show the parts beneath it. Fig. 4 shows in two views details of parts by whose operation the traveling grippers of the machine are both opened and closed.

In the said figures the same parts are indicated by like letters, as follows:

The letter A indicates the side frames of the machine; B, the impression-cylinder; C, the feed-board; C', the fly-board; R, the ink-rollers; R', water-rollers; B', the bed; G, a crank secured to a shaft, G', to be driven by any suitable means or power.

To the crank G is secured the crank-pin c,

which, by the connecting-rod c' , is connected to the shaft P' , which serves as the axis or journal of the rolling pinion P .

The stationary rack E is secured to the bed or roller-ways R^2 of the framing of the machine, and a corresponding rack, E' , is attached to the under side of the reciprocating bed of the press B' , to and between which racks the rolling pinion P is geared and rotated.

10 Journaled within the roller frame or carriage K are a series of rollers, E^2 , which are secured to shafts S , as is likewise secured the pinion P to the shaft P' , journaled in the said frame or carriage. The rollers E^2 revolve 15 and traverse within the roller-ways R^2 , and support the bed B' by its corresponding roller-ways, R^3 . This arrangement gives to the bed a rectilinear motion or length of travel double that imparted to the carriage K , thus avoiding 20 the use of a crank of inconvenient length or too great radius.

The rack R^4 is secured to the upper side of the bed B' , to which is geared the gear-wheel R^5 , secured to the impression-cylinder B .

25 The cam D upon the shaft G' , through the intervention of the roller D' , connecting-rod D^2 , crank-arm D^3 , eccentric rock-shaft D^4 , and cylinder-journal side-rods, D^5 , raises and lowers the cylinder B to clear the the types or form 30 at the proper time.

The cam F upon the shaft G' , through the intervention of the roller F' , connecting-rod F^2 , crank-arm F^3 , rock-shaft F^4 , the two attached lever-arms F^6 , and returning-springs 35 F^6 , imparts a reciprocating motion to the slides F^7 upon the guides F^8 . The guides F^8 have their ends fixed in the standards S' , secured to the frames A . The returning-springs F^6 and the connecting-rod F^2 are, for the sake of 40 clearness of illustration, omitted from Figs. 2 and 3.

The slides F^7 carry two shafts, $V^3 V^4$, respectively provided with two lower and two upper jaws, g and g' , forming two sets of traveling 45 grippers. The upper jaws, g' , and their shaft V^4 have no other motion than that due to the reciprocation or travel of the slides F^7 ; but the lower jaws, g , in addition to the same reciprocation, are caused to open and close for 50 the purpose of seizing the sheets between or releasing them from said jaws at the proper times. The grippers $g g'$ are thus operated. The lower jaws, g , are kept shut by means of the helical spring V^5 , coiled around their shaft 55 V^3 ; but when, in the course of delivery of the sheet, the small curved lever-arm V^2 , likewise secured to the shaft V^3 , is brought in contact with the roller V' upon the bracket V , it causes a partial rotation of the shaft V^3 , and consequently 60 the depression and opening of the jaw g , which opening releases the sheet from the grippers $g g'$, whence it falls upon the fly-board below. As the grippers leave the roller V they are again closed by the spring V^5 , and so 65 remain until at the other end of their travel the jaws g are again opened by the arm V^6 , loosely mounted upon the shaft V^3 , coming in

contact with the pin p , secured in the standard S' , which contact causes said arm to rise 70 against the pin p' in the curved arm V^2 , thereby turning the shaft V^3 and depressing the jaw g , thus opening the grippers for insertion of the leading edge of the sheet. At this time the slides F^7 have approached the cylinder and are nearly, though not quite, at rest. The loose arm V^6 therefore just passes over the pin p before the slides reverse, thereby releasing the jaw g , so that it is instantly closed upon the upper jaw, g' , thus holding the sheet between said jaws by the reaction of the helical spring 80 V^5 .

For clearness of illustration the grippers $g g'$ and the mechanism for opening and closing them are omitted from Fig. 2.

The bridge or fly-fingers $b b$ are placed nearly 85 at a tangent to the top of the cylinder B , their ends not quite touching it, but supported by the rod b' , the opposite ends being secured to a shaft, b^2 , journaled in the standards S' . By this arrangement said fingers may be turned 90 away from the cylinder for ready access to it and removal of the ink-rollers R . The points of the fingers b strip the sheet head first from the cylinder B , the sheet being first released by the grippers K' and raised upon the fingers b 95 by the lifter-fingers K^2 , in the manner described in Patent No. 201,226, issued March 12, 1878. When released by the traveling grippers $g g'$ the sheet falls against the sheet-stop n , forming part of the fly-board. Not being essential 100 to this invention, no devices are shown for operating the cylinder-grippers K' and lifter-fingers K^2 , and for clearness of illustration said attachments are omitted from the cylinder in Fig. 2.

105 The complete operation of the machine is as follows: The sheet, being fed to the usual guides from the feed-board C , is taken thence by the cylinder-grippers K' just as the cylinder is brought almost (and practically) to rest 110 by the arrival of the crank G at its "dead-center". Correct feeding-register is thus assured, all these parts being then in a state of least motion. The crank G then passing its center 115 commences to move the bed upon its forward or printing stroke, the cam D , through its connections above described, having at this point just brought the cylinder B down in position to make the impression. The bed thus put in motion causes the cylinder to rotate forward 120 and convey the sheet through the process of receiving the impression. When the cylinder has completed one revolution the grippers K' open and the lifter-fingers K^2 lift the advancing edge of the sheet from the cylinder B to 125 enable it to enter upon the stripper-fingers b . The cylinder B is so proportioned as to make a still further considerable fraction of a revolution in the forward or printing direction, always sufficient to bring the following edge 130 or tail of the largest sheet to be printed well clear of the bed or form. The sheet is therefore delivered by the cylinder a portion of its length upon the fingers b until its advancing edge

reaches the point X. During this operation the cam F, through its connections above described, has caused the traveling grippers *g g'* to move from the roller V' to the point X, the 5 grippers first opening and then closing upon the advancing edge of the sheet, in the manner above described, at the moment when the crank G has reached its center, and when all the parts except the crank, the cams D and 10 F, and the connecting-rod *c'* have again come to practically a state of rest. By the further rotation of the crank G the cylinder commences to retrograde, and by the action of the cam F and its connections the traveling grippers *g g'* draw that part of the sheet undelivered by 15 the cylinder from the same end over and upon the stripper-fingers *b*. Thus the surface of the cylinder and the sheet at this time move in opposite directions. The crank G, now completing 20 its rotation, brings the bed and cylinder back to their starting-points, ready to receive a succeeding sheet, during which operation the grippers *g g'*, through the operation of the cam F and its connections, draw the 25 sheet entirely off the fingers *b*, when its following edge drops upon the fly-board C' in front of the stop U, and its advancing edge is then released by the traveling grippers *g g'*, as before described, at the time when all the 30 parts except the crank G, the cams D and F, and the connecting-rod *c'* have again practically reached a state of rest.

The advantages of the objects sought and accomplished by this system or method of delivery, and never heretofore accomplished as a 35 whole in any one machine, are, in brief, as follows: the perfect facility for using the crank motion and the simplest and most direct gearing for bed and cylinder, thus not only insuring 40 perfect equality of surface velocity in bed and cylinder and entirely dispensing with buffers and springs, but also imparting to the cylinder in its rotation the same smooth and easy gradation of motion as is transmitted by the 45 crank to the bed for its rectilinear or reciprocating motion. The diameter of the cylinder is reduced to a minimum, its entire surface or periphery being utilized for making the impression, except the narrow section cut out for containing the gripper and lifter fingers and the 50 blanket-rods. The sharpest impression possible is thus obtained with a minimum strain upon the machine, as well as minimum of total weight, and therefore a corresponding maximum speed of press. The sheets are taken 55 from the feed-board by the cylinder-grippers when the cylinder is nearly or practically at rest, thus insuring accurate feed-register, and the traveling or delivery grippers both seize 60 and release the sheets when the sheets and grippers are nearly or practically at rest, thus insuring the deposit of an even pile of papers upon the fly-board. All articulation or locking and unlocking devices, intermediate gearing, universal joints, and other objectionable 65 devices in common use for causing the cylinder to rotate in one direction only, or to cause

it to "stop" during the retrograde motion of the bed for the delivery of the sheets, are entirely dispensed with. Each sheet is delivered with 70 its last-printed side upward, exposed to the inspection of the pressman for any possible defects of impression without said impression having come in contact with any part of the delivery mechanism, thus avoiding all danger 75 or possibility of smutting or soiling the work. All tapes, cords, or strings in connection with any part of the delivery are entirely dispensed with and unobstructed access obtained to the form at the back and two sides of the press. 80

The machine is not only unique as a whole, but is simpler, cheaper, and more durable than any printing-machine heretofore constructed, capable of doing the finest quality of lithographic as well as other printing in plain or 85 varied colors.

I am aware that it is not new to rotate the cylinder in one direction for making the impression and in the reverse direction for making the retrograde motion of the reciprocating 90 bed of the press, the cylinder being driven directly by the bed.

I am also aware that it is not new merely to rotate the cylinder in one direction only and to deliver each sheet head first from its top 95 upon fly or bridge-fingers, which strip the whole of the sheet from the cylinder in the manner described in Patent No. 201,226, above mentioned.

I am aware, also, that it is not new to use 100 traveling grippers for the purpose of seizing, conveying, and releasing sheets of paper in the course of delivering the same from a printing-press; but,

As of my invention, I claim—

1. A printing-machine having an impression-cylinder geared directly and continuously to a reciprocating bed and alternately rotated thereby 110 an equal distance in each direction, in combination with means, substantially as described, for taking a printed sheet head first from the top of the impression-cylinder and discharging said sheet partly during said cylinder's direct or printing rotation and partly during its retrograde or non-printing rotation, 115 substantially as and for the purposes set forth.

2. In a cylinder printing-press, in combination with a reciprocating bed and an impression-cylinder geared thereto, so as to make a greater rotation than one complete revolution 120 in each direction to a single stroke of the bed, a series of stripper-fingers and a series of traveling sheet-grippers, whereby the sheets are first partially delivered to and upon said fingers by said cylinder during a part of its forward rotation, and then during its retrograde motion removed by said grippers from said cylinder and fingers and completely delivered upon the fly-board, substantially as set forth.

JOHN T. HAWKINS.
